UNITED STATES PATENT OFFICE.

EDWARD FLANAGAN, OF PHILADELPHIA, PENNSYLVANIA.

SMOKE-HOUSE AND FUEL-ECONOMIZER.

1,138,118.

Specification of Letters Patent. Patented Mar. 23, 1915.

Application filed July 3, 1914. Serial No. 848,970.

To all whom it may concern:

Be it known that I, EDWARD FLANAGAN, a citizen of the United States, residing at Philadelphia, in the county of Philadelphia and State of Pennsylvania, have invented new and useful Improvements in Smoke-Houses and Fuel-Economizers, of which the following is a specification.

The primary object of this invention is the provision of a smoke house which economizes fuel when in operation and also insures a positive circulation of the smoke through every part of the inclosure.

The invention consists of the novel features, details of construction and combination of parts, which hereinafter will be more particularly set forth, illustrated and claimed.

In the drawings hereto attached:—Figure 1 is a vertical section of a smoke house and appliances embodying the invention. Fig. 2 is an enlarged sectional view of the fan by means of which the smoke is caused to circulate through the house and returned to the furnace. Fig. 3 is an enlarged sectional view of the smoke gatherer. Fig. 4 is an enlarged sectional view on the line $x-x$ of Fig. 1. Fig. 5 is an enlarged sectional view on the line $y-y$ of Fig. 1. Fig. 6 is an end view of the furnace.

Corresponding and like parts are referred to in the following description, and indicated in all the views of the drawings by the same reference characters.

The numeral 1 designates a smoke house which is provided at its top with the usual cupola or ventilating projection 2 and in its lower portion with a furnace 3 for burning sawdust, wood or other fuel for generating smoke which is utilized for curing purposes in the treatment of food such as meat and fish. A pipe 4 extends through a side of the ventilating projection 2 and has a depending portion upon which is fitted a hood 5 which serves the double purpose of a smoke gatherer and a valve for closing the lower end of the ventilating projection 2. The hood 5 is of conical form and is vertically adjustable. A collar 6 is formed at the center of the hood 5 and is arranged to slide upon the depending or vertical portion of the pipe 4. Flexible connections 7 are attached at one of their ends to the hood 5 and pass over pulleys 8 at the top of the projection 2 and have weights 9 at their lower

ends to counterbalance the hood and assist in the adjusting of the hood and the holding of the same in the adjusted position. When a strong draft is required as when starting the fire, the hood is lowered so the smoke and products of combustion may pass out through the openings in the side of the projection of cupola 2.

The furnace 3 has two compartments 13 and 14, the upper compartment 13 constituting the combustion chamber and the lower compartment 14 corresponding with the ash pit. A branch pipe 15 connects the upper compartment 13 of the furnace with a vertical pipe 16. A branch 17 connects the compartment 14 of the furnace with the pipe 16. Each of the branch pipes 15 and 17 is provided with a damper 18 such as indicated most clearly in Fig. 5. The pipe 16 connects at its upper end with the casing of a fan 19 and the pipe 4 also connects with the casing of the fan 19. A damper 20 is located in the length of the pipe 4 and may be regulated to admit fresh air when required.

When starting the fire in the furnace, the hood 5 is lowered, so as to establish free communication between the ventilating projection 2 and the house or structure 1, and the damper 20 is opened and the damper 15 closed and as a result the smoke from the furnace at the outset may pass off freely through the louvers in the sides of the cupola or ventilating projection 2 and fresh air drawn in through the damper 20 is carried to the furnace through the pipes 4, 16 and 17. After the fire in the furnace has been started to insure a consumption of the fuel, the hood 5 is elevated so as to close the lower end of the ventilating projection 2 and the dampers 20 and 18 of the branch pipe 15 are closed and the damper in the branch pipe 17 opened and as a result the smoke is drawn into the pipe 4 and forced into the combustion chamber 13 through the pipes 16 and 15 thereby producing a saving in the consumption of fuel since the smoke is used over and over.

From the foregoing description, taken in connection with the accompanying drawings, the advantages of the construction and of the method of operation will be readily apparent to those skilled in the art to which the invention appertains, and while I have described the principle of operation of the

invention, together with the device which I now consider to be the best embodiment thereof, I desire to have it understood that the device shown is merely illustrative, and 5 that such changes may be made when desired as are within the scope of the invention as claimed.

Having thus described the invention, what is claimed as new is:—

- 10 1. A smoke house provided in its upper portion with a ventilating projection and having a furnace in its lower portion, a hood for closing the ventilating projection, a pipe establishing communication between such 15 hood and furnace, means for creating a positive draft through the said pipe and means for adjusting the hood whereby its distance from the ventilating projection may be regulated.
- 20 2. In combination, a smoke house provided in its upper portion with a ventilating projection, a furnace located in the lower portion of the smoke house, a hood for closing the ventilating projection, means 25 for adjusting such hood and holding it in the adjusted position, a pipe establishing communication between the hood and fur-

nace, branch pipes connecting the lower portion of the main pipe with upper and lower portions of the furnace, dampers in the 30 length of the branch pipes, an independent damper located in the upper portion of the main pipe and means for creating a positive draft through the main pipe.

3. A smoke house having a ventilating 35 projection at its upper portion, a pipe having a depending portion and provided in its length with a damper, a hood for closing the ventilating projection and slidably upon the depending portion of the said pipe, means 40 for adjusting the hood vertically, a vertical pipe connected at its lower end with the furnace, a damper for regulating the discharge from the vertical pipe into the furnace and a fan in the length of the vertical 45 pipe for creating a positive draft through the pipe connection between the hood and furnace.

In testimony whereof I affix my signature in presence of two witnesses.

EDWARD FLANAGAN.
